UNITED STATES PATENT OFFICE

GUSTAV KIENE, OF EISENACH, GERMANY

TAP-HOLE SOCKET FOR BARRELS AND OTHER LIKE CONTAINERS

Application filed June 25, 1928, Serial No. 288,052, and in Germany June 30, 1927.

The subject of my invention is a taphole socket for beer barrels or other liquid containers, whether of iron, wood, or other material.

Hitherto the tap hole in the tap hole socket has been closed by means of a cork which resulted in many mishaps. Also instead of a cork bung within the bung hole, flat metallic plates have been used which arrangement, however, is also unsatisfactory. In such tap hole sockets also a thin metal cap has been employed, but, solely for protecting plates.

The invention consists in providing the socket at its inner end with a beaded flange or portion onto which a crown cork is fixed. This portion onto which the cork is fixed can either be integrally formed with the socket, or can be a separate part attached to the socket.

By this invention all the usual mishaps are avoided.

In the drawing showing an embodiment of the invention,

Fig. 1 is a side elevation of the socket; and Fig. 2 is a central longitudinal section therethrough.

a is the tapering hollow body portion having formed at one end thereof an enlarged rim portion *a*₁ and being provided adjacent thereto with a threaded portion *a*₂. *a*₃ is the tapered portion terminating in the beaded portion *a*₄, all as clearly shown in Fig. 2. *b* is the crown cap or seal of a well known construction, adapted to be crimped upon the beaded portion *a*₄ of the socket. The cap *b* comprises a circular disk-like portion *b*₁ and a marginal flange portion *b*₂ which as stated and as shown is crimped upon the beaded portion *a*₄ so as to be firmly held thereon.

The body *a* with a cap or seal *b* crimped thereon is adapted to be threaded into the bung hole of a container such as a barrel, keg or the like, whereby the contents of the container normally are prevented from escaping through the bung hole. When, however, it is desired to remove the contents of the container, the socket may be removed from the bung and the cap removed from the

socket and the latter replaced in the bung hole, or, without removing the socket from the container, the cap *b* may be punched off of the inner end of the socket by means of any suitable implement inserted through the socket.

What I claim is:

A metal tap hole socket comprising a hollow body having a screw-threaded portion for removably securing the socket within a tapped opening in a container wall with the tapered inner end of the body extending into the container, said inner end being formed with rounded bead, and a crown seal having a disc-like portion and a flange portion adapted to be crimped around said bead.

In testimony whereof I have affixed my signature.

GUSTAV KIENE.
